US0D1046666S

(12) **United States Design Patent** (10) Patent No.: **US D1,046,666 S**
(45) Date of Patent: ** Oct. 15, 2024

(54) **WATCHBAND CONNECTOR**

(71) Applicant: **Yinyan Li**, Guangdong (CN)

(72) Inventor: **Yinyan Li**, Guangdong (CN)

(**) Term: **15 Years**

(21) Appl. No.: **29/925,057**

(22) Filed: **Jan. 22, 2024**

(51) LOC (14) Cl. **11-01**

(52) U.S. Cl.

USPC **D11/94**; D10/32
